UNITED STATES PATENT OFFICE.

CHARLES SPIRO, OF NEW YORK, N. Y.

FRONT-STRIKE TYPE-WRITER.

No. 893,947.

Specification of Letters Patent.

Patented July 21, 1908.

Application filed May 5, 1906. Serial No. 315,319.

To all whom it may concern:

Be it known that I, CHARLES SPIRO, citizen of the United States, residing at New York, in the county of New York, State of New York, have invented certain new and useful Improvements in Front-Strike Type-Writers, of which the following is a specification, reference being had therein to the accompanying drawing.

10 This invention relates to a front strike typewriter and particularly to supporting means for the type bars and key levers thereof.

The invention has for an object to provide 15 a novel and improved construction of supporting frame adapted to carry both the type bars and the keys so that these members may be jointly removed from the frame of the machine and another support carrying 20 type and keys of a different character, such, for instance, as in a different language or design, readily substituted, thus permitting the assembling of the frame and carriage and also the type bars and key levers independently 25 of each other so that they may be removed whenever desired to furnish the machine with any particular design or character of type therein.

A further object of the invention is to 30 provide an improved method of mounting the type bars upon a flat or straight plate so that they may be closely nested and lie in parallel lines upon the type rest while each is in proper alinement with the printing 35 point.

Other and further objects and advantages of the invention will be hereinafter set forth and the novel features thereof defined by the appended claims.

40 In the drawings:—Figure 1 is a central cross section through the machine; Fig. 2 is a vertical section on the line 2—2, Fig. 1; Fig. 3 is a detail sectional perspective of the partially removed frame carrying the type bars and keys, and Fig. 4 is a horizontal section on line 4—4 Fig. 1.

Like numerals of reference indicate like parts in the several views of the drawings.

The numeral 1 designates the frame of the 50 machine which may be of any desired character or configuration suitable for mounting the parts therein and is provided at its front portion with a type rest 2 of any ordinary construction. Upon the rear of the top of this frame a carriage supporting way 3 is provided upon which the carriage 4 is mounted,

preferably by means of the ball bearings 5, this carriage being provided with the usual platen 6 and paper guide 7, as shown in Fig. 1. The parts so far described may be of any desired construction ordinary in the art.

Within the frame 1 a supporting plate 8 for the type and key bars is removably mounted in any desired manner, for instance, by ways 9 formed at opposite sides of the frame. This plate is preferably flat or straight as distinguished from a curved or segmental structure and may be supported in position by different means, arms or latches 10 being herein shown for that purpose. These arms are 70 pivotally mounted upon a balancing bar 11 by means of the pivots 12 so that a projection 13 from the arm is adapted to engage slots 14 disposed at the opposite sides of the plate 8. A finger piece 15 is provided upon 75 the latch arms for the purpose of readily shifting the same. The balancing bar carrying these arms is provided at its opposite ends with pivots 16 mounted in suitable bearings in the frame 1 and is provided with 80 one or more tension springs 17 extending from a connection 18 carried by the bar to a point 19 upon the frame for the purpose of counterbalancing the weight of the parts carried by this bar. 85

For the purpose of shifting the plate 8 and the parts carried thereby in a vertical plane when connected to the balancing bar, a shift key 20 is provided and pivotally mounted at 21, while the inner end 22 thereof is provided 90 with a link 23 pivotally connected to the key and the balancing bar, as shown in Fig. 1.

The type bars 24 mounted upon the shifting plate are each provided with a plurality of characters 25 at their free ends and are 95 mounted upon the plate by means of brackets 26 of ordinary construction carrying the extended or broad bearings of the bar. Extending at an angle from the pivot 27 of the type bars is a connecting arm 28 from which 100 a link 29 extends to the crank arm 30 extending upward from the type key 31, as shown in Fig. 1. This type key is provided with the usual finger piece at the keyboard of the machine, and is pivotally mounted upon the 105 cross bar 33 carried by the depending hanger 34 extending downward from the frame 35 disposed at the front of the plate 8 and carried thereby. This frame is also provided with a plurality of slotted guide plates 36 depending therefrom, each being formed with a series of parallel slots 37 therein to embrace 110

the key bars at opposite sides of their pivots and thus retain the same against any lateral movement or displacement. This type bar connection provides for the movement of the 5 type upward by a pushing action of the link connection between the crank arm of the key bar and the type bar. Each of the key bars is provided with a rearward extension 33 beyond the crank arm thereon, which is adapted 10 to engage a universal bail 39 extending transversely of the machine and common to all of the key bars. For the purpose of restoring the key bars to their normal elevated position a spring 40 is provided for each bar 15 and bears at its upper end against the plate 41 carried by the plate 8, and at its lower end is seated, as shown at 42 upon the upper face of the key bar. Each key bar is also provided 20 at the front of the frame 35 with the stop lug 43 to limit the upward movement thereof.

The type bar brackets 26 are disposed upon the plate 8 at different distances from the printing point on the platen 6 in series at 25 successively greater angles from said point. This mounting is accomplished by the apertures 44 in the plate 8, as shown in Figs. 2 and 3, through which the shanks of the brackets 26 are passed and secured by any 30 desired means. These points of mounting the type bars also recede successively inward, for instance, in a descending line, and for the purpose of permitting the use of type of uniform length and leverage the brackets 35 are formed of different lengths. By reference to Fig. 2 it will be seen that the mounting apertures or points on the plate 8 are located in a series of lines disposed diagonally to the longitudinal axis of the platen, 40 and the angle therefrom to the printing point upon the platen varies for each bar. This permits the nesting of the type bars containing a plurality of type in parallel lines when at rest, and also affords a clear path for each 45 bar to the printing point without danger of interference thus materially economizing the space required for the disposition of the bars when at rest and permitting the use of a greater number of type bars within a given 50 area of space than heretofore.

The universal bar 39 is pivotally mounted upon a cross rod 45 carried by the bracket 46 disposed at the rear of the plate 8, and the bar is provided with an upwardly extending arm 47 disposed in contact with or adjacent to a depending arm 48 carried by the dog mechanism 49, which is pivotally mounted at 50 and adapted to engage the rack bar 51 in the usual manner. This dog mechanism 55 is provided with an inwardly extending pin 52 for operating the ribbon vibrating or shifting mechanism. This mechanism comprises a ribbon carrier 53 disposed between the ribbon spools 54 which are mounted in 60 the usual manner upon the frame of the machine, and the carrier is formed with an angularly disposed portion 55 extending beneath the carriage and pivotally mounted upon the frame at 56. From this pivot a downwardly extending apertured plate 57 70 extends through which the operating pin 52 from the dog passes. It will be seen that an oscillation of the dog causes a movement of the ribbon carrier upon its pivot which results in an upward travel of the ribbon from 75 the position shown by full lines below the printing point on the platen to said printing point so that the type engages the ribbon at its point of impression and when the key bar is released the ribbon drops to a point below 80 the printing point so as to permit a clear observation of the printed line without interference by the ribbon. For the purpose of operating the dog for spacing, a space key 58 is provided and pivotally mounted at 59, 85 while the rear portion thereof is provided with an upward projection 60 disposed beneath the universal bail to engage the same upon the depression of the space key.

In the operation of the typewriter the depression of the key lever throws the type bar upward into contact with the platen, as shown by dotted lines in Fig. 1, and at the same instant the motion communicated by the rear end of this lever causes the ribbon 90 guide to be oscillated toward the platen to interpose the ribbon between the type and the platen. The carriage is provided with any ordinary or usual form of escapement mechanism and other auxiliary parts not herein illustrated as they form no part of the present invention.

The holding plate or support is adapted to carry both the type bars and the key bars together with their connecting mechanisms so that these parts are bodily removable from the frame of the machine which is an important feature of construction as it permits the manufacture and storage of different characters of type and key bars ready for 100 application to any character of frame by which type in different languages may be used or the character or design of type in any machine readily changed from time to time. For the purpose of effecting this removal it is 110 simply necessary to disconnect the counterbalancing means from the plate and by shifting the holding arms laterally thereof so as to disengage from the slots of the plate, when the parts may be removed through the base 120 of the machine and new parts introduced. By a reversal of this operation the structure herein shown permits the use of this retaining arm for the plate both as a means for vertically shifting the plate and for preventing its accidental removal from the machine. As hereinbefore stated, the manner of mounting the type bars upon this plate is such as to greatly economize in the space required and permit the type of each bar 130

when upon the rest to lie in parallel planes, and obviates the necessity of bending the type bars to bring the type thereon into alinement with the printing point, which is 5 very objectionable in many instances as any pressure upon the bars is liable to change the exact position thereof and this affect the alinement of the machine which is also to a large extent produced by the hammer or 10 blow of the bar against the platen, so that it is particularly important to use a straight bar extending in a direct line from the printing point to its hanger.

Having described my invention what I 15 claim and desire to secure by Letters Patent is:

1. In a typewriter, a frame, a support mounted to slide vertically therein, type bars carried by said support, key bars having 20 their pivots in said support, and means for reciprocating said support for shifting the type and key bars.
2. In a typewriter, a frame, a support slidably held therein, type bars carried by said 25 support, key bars having their pivots therein, means operable from the keyboard for reciprocating said support vertically, and means extended from the reciprocating means to the frame for counterbalancing the 30 weight of said support.
3. In a typewriter, a frame, a support removably held therein, type bars carried by said support, key bars carried thereby, means operable from the keyboard for shifting 35 said support vertically, means for counterbalancing the weight of said support, a ribbon shifting mechanism disposed adjacent to said support, and an extension from said key bar to operate said mechanism.
4. In a typewriter, a frame, a support removably held therein, type bars carried by 40 said support, key bars carried thereby, means operable from the keyboard for shifting said support vertically, means for counterbalancing the weight of said support, a ribbon shifting mechanism disposed adjacent to 45 said support, an extension from said key bar to operate said mechanism, and a hanger upon the front face of said support and provided with a pivotal bearing for said key bars.
5. In a typewriter, a frame, a support removably held therein, type bars carried by 50 said support, key bars carried thereby, means operable from the keyboard for shifting said support vertically, means for counterbalancing the weight of said support, a ribbon shifting mechanism disposed adjacent to 55 said support, an extension from said key bar to operate said mechanism, a hanger upon the front face of said support and provided with a pivotal bearing for said key bars, and an upwardly extending crank arm from said key bars operatively connected to 60 said type bars.
6. In a typewriter, a platen, a frame, a

straight supporting plate slidably mounted in the frame below said platen, a series of type bar hangers mounted upon one face of said plate in lines extending at different angles from the printing point on the platen 70 and successively one beneath the other, type bars mounted in said hangers and key bars carried by said supporting plate and operatively connected to said type bars.

7. In a typewriter, a platen, a frame, a 75 straight type bar supporting plate slidably mounted in said frame and provided with a series of bar supporting means disposed in different vertical planes and in successive horizontal planes upon the front face of said 80 plate, and a key bar support carried by the lower portion of said plate.

8. In a typewriter, a type bar supporting plate provided with a series of bar supporting means disposed in different vertical planes 85 and in successive horizontal planes and the pivotal points of said bars receding toward the plate downwardly of the series, a key bar support carried at the lower portion of said plate, and a key bar mounted therein.

9. In a typewriter, a platen, a straight supporting plate provided with a series of type bar supporting means upon the front face thereof, a frame provided with guides to slidably support said plate relative to said 95 platen, and a series of key levers carried by said plate.

10. In a typewriter, a straight supporting plate provided with a series of type bar supporting means thereon, a frame provided 100 with guides to removably support said plate, and a shifting lever mounted upon said frame and provided with a latch to engage a horizontally disposed slot in said plate.

11. In a typewriter, a straight supporting plate provided with a series of type bar supporting means thereon, a frame provided with guides to removably support said plate, 105 a shifting lever pivotally mounted upon said frame, and a plate engaging arm pivotally mounted upon said lever to travel toward and from one end of said plate and engage therewith.

12. In a typewriter, a straight supporting plate provided with a series of type bar supporting means thereon, a frame provided 115 with guides to removably support said plate, a balancing bar for said plate pivotally mounted upon said frame, a plate engaging arm pivotally mounted upon said bar to travel toward and from one end of said plate and engage therewith, and a counterbalancing spring extending between said bar and frame.

13. In a typewriter, a frame supporting 125 plate removably held therein, a type bar carried thereby, a depending hanger carried by the lower portion of said plate, a key bar pivotally mounted upon said hanger, a crank arm extending upward from said key bar to 130

said type bar, and a restoring spring carried by said plate to act upon said key bar.

14. In a typewriter, a key lever provided at its inner end with an extension therefrom adapted to engage a ribbon vibrating connection and intermediate of its ends with an angularly disposed arm adapted to actuate a type bar.

15. In a typewriter, a frame, a type bar supporting plate carrying a depending slotted key lever guide, a pivoting bar disposed at the lower edge of said guide and parallel thereto, and a key lever extending through said guide and having a pivotal bearing upon the upper face of said pivoting bar.

16. In a typewriter, a frame, a supporting plate, a key lever guide comprising a depending slotted plate, a depending pivoting bar at the front of said slotted plate, a key lever

extending through said plate and having a pivotal bearing upon the upper face of said pivoting bar, and a restoring spring extending between said supporting plate and the upper surface of a key lever at the rear of said guide.

17. In a typewriter, a frame, a support or plate mounted to reciprocate vertically therein, a carriage mounted upon the frame above said plate and provided with a platen, a series of type bar hangers of different lengths and disposed in successive horizontal planes upon the outer surface of said plate, type bars mounted in said hangers and provided with a plurality of characters thereon, and levers carried by said plate for operating said bars.

18. In a typewriter, a frame, a vertically shifting plate therein, type bars carried by said plate, a shifting lever for said plate pivotedly mounted in the frame of the machine, a balancing bar connected to said lever, and an arm carried by said bar and pivotally mounted to swing in a horizontal plane into engagement with said plate.

45 19. In a typewriter, a frame, a vertically shifting plate therein, type bars carried by said plate, a shifting lever for said plate pivotedly mounted in the frame of the machine, a balancing bar connected to said lever, an arm carried by said bar and pivotally mounted to swing in a horizontal plane into engagement with said plate, a hanger depending from the lower portion of said plate, a key lever carried by said hanger and connected to said type bar, and restoring means for said key lever.

20. In a typewriter, a frame, a vertically shifting plate therein, type bars carried by said plate, a shifting lever for said plate pivotally mounted in the frame of the machine, a balancing bar connected to said lever, an arm carried by said bar and pivotally mounted to swing in a horizontal plane into engagement with said plate, a hanger depending from the lower portion of said plate, a key

lever carried by said hanger and connected to said type bars, a ribbon vibrator pivotally mounted upon the frame, and an extension from the inner end of the key lever at the rear of said plate to engage an operating connection for said ribbon vibrator.

21. In a typewriter, a frame, a balancing bar pivotally mounted therein, a type bar plate slidably mounted in said frame, and latch arms carried by the balancing bar to engage said plate at its sides.

22. In a typewriter, a frame, a balancing bar pivotally mounted therein, a type bar plate slidably mounted in said frame, latch arms carried by the balancing bar to engage said plate at its sides, a pivotally mounted key lever for shifting said plate, and a connection between said key lever and the balancing bar.

23. In a typewriter, a frame, a balancing bar pivotally mounted therein, a type bar plate slidably mounted in said frame, latch arms carried by the balancing bar, a pivotally mounted key lever for shifting said plate, a link connection between said key lever and balancing bar, and a projection carried by said arms to engage said plate.

24. In a typewriter, a frame, a balancing bar pivotally mounted at the rear thereof, a tension spring extended from said balancing bar to said frame, an outward extension at the opposite ends of said balancing bar, a type bar plate disposed between said extensions, and latch arms upon said extensions to engage said plate at its sides and connected to the balancing bar.

25. In a typewriter, a frame, a universal bail pivotally mounted therein, a type bar, a key lever pivoted intermediate of its ends and provided with an angularly disposed arm connected to said type bar, and an extension from the rear of the key lever disposed beneath said bail.

26. In a typewriter, a frame, a universal bail pivotally mounted therein, a type bar, a key lever provided with a crank arm connected to said type bar, an extension from the key lever disposed beneath said bail, a ribbon vibrating mechanism, and an upwardly extending lever from said bail to operate said mechanism.

27. In a typewriter, a frame, a universal bail pivotally mounted therein, a type bar, a key lever provided with crank arms connected to said type bar, an extension from the key lever disposed beneath said bail, a ribbon vibrating mechanism, an upwardly extending lever from said bail to operate said mechanism, and an oscillating dog mechanism connected to said ribbon vibrator and having a depending arm in the path of said lever.

28. In a typewriter, a frame, a supporting plate therein, type bars mounted upon said plate, a frame carried by the front of said

plate at its lower portion, a depending pivoting bar from said plate frame, and key levers pivotally mounted upon the upper face of said bar.

5. 29. In a typewriter, a frame, a supporting plate therein, type bars mounted upon said plate, a frame carried by the front of said plate at its lower portion, a depending pivoting bar from said plate frame, key levers pivotally mounted upon said bar, and depending slotted guide plates disposed at opposite sides of the pivoting bar and embracing the key lever.

10. 30. In a typewriter, a frame, a supporting plate therein, type bars mounted upon said plate, a frame carried by the front of said plate at its lower portion, a depending pivoting bar from said plate frame, key levers pivotally mounted in said bar, depending 15 slotted guide plates disposed at opposite sides of the pivoting bar and embracing the key lever, a cross plate carried by the plate frame, and a restoring spring extending therefrom and seated upon the upper 20 surface of the key lever.

25. 31. In a typewriter, a frame, a support slidably mounted therein, type bars carried by said support, key levers pivoted upon said support, means for reciprocating said 30 support for shifting the type bars, and a

movable device for detachably retaining said support within the frame to permit its bodily removal therefrom with the type bars.

32. In a typewriter, a frame, a platen disposed in a substantially horizontal plane, a 35 sliding support disposed in substantially a vertical plane, means for reciprocating said support toward and from said platen, a series of type bars each having laterally disposed bearings and independent brackets upon 40 said support, and a series of key levers pivotally carried by said support and connected to said bars.

33. In a typewriter, a frame, a platen disposed in substantially a horizontal plane, a 45 support disposed in substantially a vertical plane, means for shifting said support toward and from said platen, a series of type bars each having laterally disposed bearings and independent brackets mounted upon said 50 support in a plurality of lines and staggered relative to each other, and a series of key levers pivotally carried by said support and connected to said bars.

In testimony whereof, I affix my signature 55
in presence of two witnesses.

CHARLES SPIRO.
